UNITED STATES PATENT OFFICE

124,885

DESIGN FOR A MIXING SPOON FOR GRAVY, SAUCE, OR THE LIKE

Erna Zwickly, Milwaukee, Wis.

Application March 15, 1940, Serial No. 90,927

Term of patent 7 years

To all whom it may concern:

Be it known that I, Erna Zwickly, a citizen of the United States, residing at Milwaukee, in the county of Milwaukee and State of Wisconsin, have invented a new, original, and ornamental Design for a Mixing Spoon, for Gravy, Sauce, or the like, of which the following is a specification, reference being had to the accompanying drawing, forming part thereof.

Figure 1 is a perspective view of a mixing spoon, for gravy, sauce, or the like, showing my new design; and

Figures 3, 4 and 5 are cross-sectional views taken respectively along lines 3—3, 4—4, and 5—5 of Figure 2.

I claim:

The ornamental design for a mixing spoon, for gravy, sauce, or the like, as shown.

ERNA ZWICKY.
